UNITED STATES PATENT OFFICE.

FRANK P. MILLER, OF DOWNTON, PENNSYLVANIA.

SCREEN-BOX FOR PAPER-MAKING MACHINES.

1,354,324.

Specification of Letters Patent. Patented Sept. 28, 1920.

Application filed January 2, 1919. Serial No. 269,228.

To all whom it may concern:

Be it known that I, FRANK P. MILLER, a citizen of the United States, and a resident of Downingtown, county of Chester, State 5 of Pennsylvania, have invented certain Improvements in Screen-Boxes for Paper-Making Machines, of which the following is a specification.

The main object of my invention is to im-
10 prove the means for operating the suction mechanism of a screen box of a paper making machine, whereby the screens can be ar- ranged side by side and at different levels, and operated directly from a single shaft
15 extending transversely through the several screen structures.

A further object of the invention is to relieve the power mechanism of the weight of the suction boxes.

20 A still further object of the invention is to provide a rocking means for actuating the screen boxes.

The invention relates also to further de-
tails which will be described hereafter.

25 In the accompanying drawings:—

Figure 1, is a plan view of a series of screen boxes, illustrating my invention and showing them connected to the vats of a paper making machine;

30 Fig. 2, is a front view of the screen boxes showing them arranged on different levels;

Fig. 3, is a side view looking in the direction of the arrow 3, Fig. 1;

Fig. 4, is a side view of one of the screen
35 boxes;

Fig. 5, is a plan view of one of the screen boxes;

Fig. 6, is an end view;

Fig. 7, is a diagrammatic view showing
40 the connection from the driving shaft to the several rockers which operate the suction devices;

Fig. 8, is a detached view of the cam shaft;

45 Fig. 9, is a sectional view of a portion of the screen box, showing one of the suction devices; and

Fig. 10, is a view illustrating a modifica-
tion of the invention.

50 1, 1 are the screen boxes, six in the present instance, arranged side by side, and 2 is a separate box for receiving material from the other boxes and re-screening it. The material passing through the screen

boxes 1 is discharged through pipes 3 to the 55 pumps 4, which in turn connect with pipes 5 leading to the vats 6 of a paper making machine. This machine is of the ordinary construction and the vats are arranged at different levels for the purpose of allowing 60 the couch roll to be so located that the water will flow back into the vat as the paper is being formed.

It is of advantage to have the screen boxes at a certain level above the vats, and I have 65 found that by arranging the boxes on levels corresponding to the levels of the several vats I obtain a more even flow of material from all of the screen boxes to the vats and, consequently, a much better grading of the 70 pulp is the result than if the height of the screen boxes in respect to the vats is varied.

Heretofore to accomplish this it was nec-
essary to independently drive the mech-
anisms of each of the screen boxes, and it was 75
the common practice to arrange them end
to end rather than side by side and to mount
on each box a longitudinal shaft and drive
these individual shafts from a long counter
shaft.

By my invention, however, I am enabled
to arrange the boxes side by side, taking up
a comparatively small amount of space, and
I drive the mechanism from a single shaft
7 running transversely through the series of 85
boxes, and this shaft is made up of a series
of sections connected together by couplings
8 at the spaces between the several boxes, as
clearly shown in Fig. 1. This shaft is
driven from a belt which passes around a 90
belt wheel 9 on one end of the shaft 7.

The pump shaft 10 is driven by a belt in
the present instance, and is made up of a se-
ries of sections passing through the several
pumps 4, and these sections are connected 95
together by couplings, as shown by dotted
lines in Fig. 1.

By the above arrangement any one of the
screen boxes can be uncoupled and entirely
removed, if necessary, and replaced, or a 100
short coupling shaft may be used to connect
the sections of the remaining boxes, if neces-
sary.

Each box 1, as shown in Fig. 4, is mount-
ed on standards 11 and connected by a cross 105
piece 12 on which are bearings 13 for the
pivots 14 of the three-armed rockers 15.
There are two of these rockers in the pres-

ent instance and the two lateral arms of the rockers are connected to the depending bearings 16 of the suction device 17, shown by dotted lines in Fig. 4. These suction devices are of the ordinary construction.

10 The depending arm 18 of each rocker is pivotally connected at 19 to a bar 20 having a depending portion 21 connected by an eccentric rod 22 to an eccentric 23 on the shaft 7. The shaft is mounted in bearings 24 secured to the standards 11 of the several screen boxes.

15 It will be noticed, in referring to Fig. 2, that the several boxes are arranged on different levels and in order to connect the several bars 20 to eccentrics on the shaft 7 and to have the same amount of throw on all of the suction devices, I gradually raise the pivot 25 equal to the level of the several 20 screen boxes so that, while each device is rocked independently, the rocking action is the same on all boxes, see Fig. 7.

25 It will be noticed that the weight of the suction devices is taken by the beam 12 through the bearings 13 on which the pivots 14 of the rockers are mounted, and that one suction device of each set balances the other. Heretofore it was the usual practice to operate the suction boxes by cams on longitudinal shafts, the cams taking the full 30 weight of the suction devices as well as operating them. This made it necessary to frequently renew the bearings and also to renew the cams, but by the construction 35 shown the pivot takes the weight and there is very little power required to operate the suction devices, as one device balances the other.

40 Each box has a screen 25, preferably made in sections; the perforations in the screen may be of any size desired depending upon the character of paper being manufactured. The suction devices 17 are located under the screens and are constructed in the present instance as shown in Fig. 9. The bearings 16 are attached to heads 26; each head is located in an opening 27 in the bottom of the screen box and a sheet of rubber 28, or other suitable material, is secured to the 45 bottom and to the head as shown, and as the compartments 29 under the screens 25 are separated one from another the short vertical movement imparted to the head will be sufficient to draw the paper stock of a 50 certain fineness through the screens while the remaining stock is carried forward by flights 30 on endless chains 31 and discharged into a trough 32. The material 55 flows through this trough to the screen 2, where it is re-screened.

60 The chains 31 pass around sprocket wheels 33 and 34 mounted on shafts 35 and 36, respectively, and in the present instance the shaft 35 is a driven shaft having a gear 65 wheel 37 thereon which meshes with a pin-

ion 38 on a shaft 39 driven from an overhead shaft 40, as shown in Fig. 3; this overhead shaft 40 extends longitudinally past all of the screens and is independently belted to the shaft 39 of each screen box. The 70 flights 30 not only carry the coarse material forward and discharge it into the trough 32, but act to hold the water back so as to allow it to flow with the pulp through the screen.

75 While I have shown two pairs of suction devices in each screen box, it will be understood that a single pair can be used without departing from the invention, and while I have shown two three-armed rockers and a connecting bar which in turn is connected 80 to the eccentric rod, the construction illustrated in Fig. 10 may be used, in which two two-armed rockers 15^a are shown and in which one of the arms is extended as at 18^a and connected by eccentric rods 22^a to eccentrics on the shaft 7^a. In this instance the 85 suction devices are also balanced.

90 It will be seen, therefore, by the above description that I am enabled to drive the suction mechanism of a series of screen boxes 95 from a single shaft extending transversely under the suction boxes, and to balance the several suction devices and mount them on a pivot supported by the frame of the machine so as to relieve the driving mechanism 95 from a material portion of the weight and consequently reduce the power necessary for operating the screen boxes.

I claim:—

1. The combination in a paper making 100 machine, of a series of screen boxes each having independent suction mechanism, said boxes being arranged at different levels and located side by side; a shaft extending under the several boxes and having an eccentric 105 at each box and an eccentric rod coupling each eccentric to a suction mechanism.

2. The combination of a series of screen boxes arranged at different levels and located side by side, each box having suction 110 mechanism; a shaft common to all of said boxes and made in sections, the coupling of the sections being located between the boxes; an eccentric on each section; and a rod coupling each eccentric to one of the suction 115 mechanisms.

3. The combination in a screen box, of two three-armed rockers, each rocker having a pivot; bearings for the pivots; suction devices; two of the arms of each rocker being 120 connected to the suction devices; a rod connecting the other arms of the rockers; a driven shaft; an eccentric therein; and an eccentric rod connecting the eccentric to the rod of the rockers.

125 4. The combination of a series of screen boxes arranged side by side; suction devices forming part of each screen box; two three-armed rockers located under each box; two arms of each rocker being attached to suc- 130

tion devices; a connecting rod attached to the third arm of each rocker; the screen boxes being arranged at different levels; a shaft extending transversely under the several boxes and having eccentrics thereon; and eccentric rods coupling an eccentric with the connection of each screen box.

5. The combination of a series of screen boxes arranged side by side; screens in each 10 box; suction devices also in each box; endless chains and flights thereon arranged to control the flow of material over the screens; a single shaft extending past the several 15 boxes; and means for driving the endless chains of the several boxes from said shaft.

6. The combination of a series of screen boxes; screens and suction mechanism therein; means for controlling the flow of the material over the screens; and a trough common to all of said boxes to receive the material from each box which needs re-screening.

7. The combination of a series of screen boxes; screens and suction mechanism therein; means for controlling the flow of the material over the screens; a trough common to all of said boxes to receive the material from each box which needs re-screening; and

a re-screening box at one end of the series of boxes into which the trough discharges.

8. The combination in a paper making machine of a series of screen boxes arranged side by side and at different levels; a horizontal shaft extending under the several boxes and having bearings; two rockers for 35 each screen box; a connecting bar connecting the rockers of each screen box; an eccentric on the shaft at each box; and a series of rods connecting the eccentrics with said bars.

9. The combination of a series of screen 40 boxes arranged at different levels and located side by side; a longitudinal shaft extending under all the boxes, each box having suction devices; two three-armed rockers, each rocker being connected to the suction devices; a bar to which the third arm of each rocker is connected, each bar having a depending portion; an eccentric on the shaft at each suction box; and an eccentric rod coupling the eccentric with the depending portion of each bar, the pivots for the rods being located at different points on the bar according to the level of the screen box.

In witness whereof I affix my signature.

FRANK P. MILLER.
